CARTON INSERT FOR SHIPPING CATHODE-RAY PICTURE TUBES

Thomas J. Deeren, 1862 Glen Ellyn Drive,
Toledo, Ohio 43614

Filed Aug. 19, 1968, Ser. No. 13,185

Term of patent 14 years

Int. Cl. D9—04

U.S. Cl. D9—188

FIG. 1

FIG. 2

FIG. 4

FIG. 3

FIG. 6

FIG. 5

FIGURE 1 is a top plan view of the carton insert for shipping cathode-ray picture tubes, said insert embodying my new design.

FIGURE 2 is a perspective view thereof.

FIGURE 3 is an enlarged front elevational view thereof.

FIGURE 4 is an enlarged side elevational view thereof.

FIGURE 5 is an enlarged sectional view taken along the line 5-5 of FIGURE 2.

FIGURE 6 is an enlarged sectional view taken along the line 6-6 of FIGURE 2.

I claim:

The ornamental design for a carton insert for shipping cathode-ray picture tubes, as shown.
